UNITED STATES PATENT OFFICE.

CASS L. KENNICOTT, OF CHICAGO HEIGHTS, ILLINOIS, ASSIGNOR OF ONE-HALF TO THE PERMUTIT COMPANY, OF NEW YORK, N. Y., A CORPORATION OF DELAWARE.

WATER-SOFTENING APPARATUS.

1,272,052.

Specification of Letters Patent.

Patented July 9, 1918.

Application filed March 20, 1916. Serial No. 85,383.

To all whom it may concern:

Be it known that I, CASS L. KENNICOTT, a citizen of the United States, residing at Chicago Heights, in the county of Cook and 5 State of Illinois, have invented a new and useful Improvement in Water-Softening Apparatus, of which the following is a specification.

My invention relates to improvements in 10 apparatus for softening hard water, more particularly to that form of apparatus in which certain base-exchanging substances are utilized as reagents.

The object of this invention is to provide 15 a form of apparatus in which these substances, for instance the zeolites, may be used most economically and conveniently. The invention will be fully understood from the following detailed description, taken in 20 connection with the accompanying drawing which illustrates in longitudinal vertical section one form of apparatus embodying the invention.

In the drawing 1 designates a vertical cylindrical drum, provided with upper and lower convex heads 2 and 3. Adjacent the upper head a valved inlet pipe 4 is tapped in through the wall of the drum, and in the center of the lower head a valved outlet pipe 5 is provided. A short distance above the lower head is mounted a reticulated partition 6 on which lies a relatively thin bed of gravel 7. This gravel bed supports and prevents the escape of a relatively large 35 mass of the active water softening agent, such as the zeolites referred to, in the form of a finely divided permeable mass.

On the top of the bed 8 there is a second gravel bed 9, also relatively thin, and terminating some distance below the inlet pipe 4. In the center of the convex head 2 there is mounted a valve housing 10, having an inwardly facing valve seat 11 at its upper end, opening to a vent pipe or directly to the atmosphere as shown, a ball float 12 having a valve member 13 adapted to engage the seat 11, being mounted within the casing and guided by a depending stem 14.

The operation of my apparatus is as follows:

The hard water to be softened will enter through the pipe 4, filling the chamber above the upper gravel bed 9, and rising within the valve casing 10 will lift the float 12

upwardly, thereby automatically seating the 55 valve 13 and preventing escape of the water. When a sufficient pressure has accumulated within the upper chamber of the apparatus the water will begin to percolate through the gravel bed 9, being thus retarded and 60 brought to a uniform downward velocity throughout the cross section of the apparatus, and will pass through the layer of active water softening material 8, through the lower gravel bed 7, and out of draw-off 65 or outlet pipe 5.

It will be understood that the water softening action of the base-exchanging substance is in general purely a surface reaction. That is, it takes place only through 70 the contact of the hard water with the surfaces of solid base-exchanging substance. It will further be well understood by those familiar with the art that such base-exchanging substances have only a limited activity, becoming spent in a relatively short 75 time and requiring regeneration with chemicals before they may be further used. By reason of these considerations it is of the utmost importance that the water passing 80 through the bed of softening material be permitted to contact with the maximum surface of the material, and furthermore that the speed or rate of flow of the water through the bed be uniform throughout its 85 cross section and length. This consideration applies equally to the process of regeneration, in which the regenerating substance in the form of an aqueous solution is passed through in exactly the same manner as is 90 the water to be softened.

The desired results are obtained in the form of apparatus illustrated in the simplest and most effective manner. The incoming 95 stream of raw water, which in general practice will be pumped through the pipe 4 under considerable pressure, will completely fill the chamber above the gravel bed 9, and exert a uniform downward pressure over the entire cross-sectional area thereof, any air which is contained within the water rising to the surface and escaping through the valve opening in the casing 10. It is only when the chamber has been completely 100 filled and the water has risen to the level of the float 12 that the valve will be closed. A solid column of water will therefore move downwardly through the apparatus at a uni-

form rate at every point of its cross section, utilizing all of the available contact surface of the material under such conditions that all of the mass will become "spent", at the 5 same time. It will of course be understood that in the usual operation of the apparatus more or less air will continually enter with the incoming stream of water and such entering air will promptly rise to the surface 10 of the relatively quiescent body above the bed 9, and a sufficient quantity of air having accumulated within the valve housing 10, float 12 will drop and permit its escape in the manner before described. The apparatus 15 therefore acts automatically to maintain the desired condition of affairs at all times.

The operation and advantages of the structure during the regenerating of the softening re-agent will be the same. 20 While I have shown and described in considerable detail one specific embodiment of my invention, it is to be understood that this showing and description is illustrative only and for the purpose of making the invention 25 more clear, and that I do not regard my invention as limited to these details of con-

struction, nor to any of them, except in so far as I have included such limitations within the terms of the accompanying claims in which it is my intention to claim all novelty 30 inherent in my invention as broadly as is permissible in view of the prior art.

What I claim is new, and desire to secure by Letters Patent is:

A water-softening apparatus comprising 35 a vertical drum, a raw water inlet in the upper portion of the drum, a softened water outlet in the lower portion of the drum, a permeable bed of base-exchanging substance arranged to afford a uniform cross-sectional 40 area throughout its depth and mounted in the intermediate portion of the drum and below the said inlet, a float lying above the said bed and an air outlet valve actuated by the float, whereby a solid column of water 45 may move downward at a uniform velocity through the entire cross-sectional area of the bed.

CASS L. KENNICOTT.
